In Great Britain January 15, 1946

3 Claims. (Cl. 87—50)

1

The present invention relates to braiding machines and is primarily concerned with machines used for the braiding of non-elastic or elastic cores such as the braiding of wire or the production of elastic braid. The present invention relates in particular to braiding machines for this purpose of the type in which a sinuous path is imparted to the wanderer spindles by means of notched discs carrying same.

Hitherto braiding machines of the type referred to have been provided with a continuous sinuous track adapted to be engaged by a lug or lugs formed at the lower end of each wanderer spindle and the said wanderer spindles have been propelled around the said continuous track by means of notched discs.

The disadvantage of the arrangement as at present used is that a considerable amount of friction and wear takes place between the lugs of the wanderers and the continuous guide track and also between the flange faces of the wanderer spindles and the guide track plate.

The object of the present invention is to dispense with a continuous sinuous track thus reducing a source of friction with a consequent reduction of wear and power required to drive the machine.

The present invention is characterized by the provision of guide track members only at the circumferential junctions of the notched discs to effect a guiding or transference of the wanderer spindles between the said adjacent notched discs.

In the accompanying drawings,

Figure 1 is a plan view of a base member of the improved braiding machine according to the present invention.

Figure 2 is a sectional view similar to Figure 1 taken substantially on the line *ii*—*ii* of Figure 3.

Figure 3 is a sectional view in elevation taken on the line *iii*—*iii* of Figure 1.

Figure 4 is a plan view of one of the change over guide track members per se.

Figures 5 and 6 are cross sectional views on the line 5—5, 6—6, of Figure 4, respectively.

Figure 7 is a view of a wanderer spindle adapted for use with braiding machines of the type with which the present invention is concerned, and

Figures 8 and 9 are sectional views on an enlarged scale of the lugged end of the wanderer engaging the aforesaid guide track members.

The accompanying drawings illustrate the present invention applied to a braiding machine em-

ploying wanderer spindles and arranged for producing flat braid.

Referring to Figures 1 to 3 the base member 1 is mounted on the machine bed 2 in a horizontal manner said base member 1 being recessed at its upper side to form a shallow oil receptacle 3.

Arranged in said base member 1 are a plurality of bushes 4 adapted to form bearings for the sleeves 5 formed integral with each of the notched discs 6, 7, 8, 9, 10, 11. Keyed to the lower ends of each of the sleeves 5 are gears 12, 13, 14, 15, 16, 17, arranged in geared relationship, Figure 2, such that the said gears and discs are all driven in synchrony from a driving gear 18 driven by an electric motor or the like. The sleeves 5 are also provided with lower bearings 19.

The oil receptacle 3 is enclosed by the aforesaid notched discs together with a substantially star shaped inner member 20 and a suitably shaped outer member 21, said members 20 and 21 intimately surrounding all of said notched discs to also provide retaining and supporting means for the said wanderer spindles 22.

Each wanderer spindle 22, of which one only is shown in position in Figures 1 and 3 for reasons of clarity, is provided with a location dog 23 adapted to engage the notches 24 of the notched discs 6, 7, 8, 9, 10, 11, and be carried in turn thereby.

Each wanderer spindle follows a sinuous path and its transference from one disc to the other is effected by means of change over guide track members or inserts 25 mounted in the oil receptacle 3 and positioned under the said notched discs at points where their circumferences are adjacent to each other. The arrangement being that the lug 26 formed at the lower end of each wanderer spindle engages a change over insert 25 at the same time as the engaged notch of the disc carrying said spindle comes opposite a notch in an adjacent disc, the notches being suitably positioned and spaced. For example, as shown in Figure 1, the wanderer spindle 22 carried by the notched disc 8 is in a position just after having been transferred thereto from the notched disc 7 by means of the change over insert 25.

Figure 9, shows on an enlarged scale, a lug 26 of a wanderer spindle 22 engaging a cross over insert 25.

For producing flat braid the arrangement is as shown i. e. change over inserts 25 are arranged between all the notched discs except between discs 6 and 11, where a return insert 27 is provided so that a transfer is not effected between these discs. Thus by first following the arrows

shown in full from the return insert 27 and then following the dotted arrows the sinuous path of each wanderer spindle 22 is traced. This cycle is, of course, repeated many times by each wanderer spindle when the machine is in use. Figures 3 and 8 show the wanderer spindle engaging the return insert 27 whereby the wanderer spindle is retained on the notched disc 6 at this point.

For producing round braid the return insert 27 is replaced by a change over insert 25 whence a sinuous path of a more continuous nature is imparted to the wanderer spindles.

In either case the cores, which may be elastic are passed up the vertical tubes 28 to a common eye in a gauge disc fixed about the longitudinal axis of the machine in accordance with established practice.

It will also be observed that in either case the lugs 26 of the wanderer spindles instead of being engaged by a continuous sinuous track are only engaged by the aforesaid inserts 25 or 27 for short periods thus the period of frictional wear is greatly reduced and moreover the provision of an oil receptacle enhances the longevity of the parts.

Associated with the thread tensioning means 30 of each wanderer spindle 22 is a member 31 provided with a hook 32 engaged by the thread 33 as it passes from the lower "pigtail" 34 to the upper "pigtail" 35.

In the event of the thread 33 breaking, the member 31 descends the slot 36 of the thread tensioning means so that within the course of one cycle of the sinuous path of the wanderer spindle the member 31 actuates the bar 37 of an electric switch 38 controlling the machine motor to break the circuit thus stopping the machine. In this way the occurrence of a broken thread is brought to notice and can be readily attended to.

It will be appreciated that whereas the invention has been described with reference to a machine employing thirteen wanderer spindles the invention can be equally well applied to machines employing a greater or less number of wanderer spindles and a varying number and size of notched discs.

The arrangement described may form a unit of a series of units forming a complete machine capable of simultaneously producing several lengths of braid.

We claim:

1. Improvements connected with braiding machines comprising in combination a base member; a plurality of circumferentially adjacent notched discs in driven geared relationship mounted on said base member and adapted to engage only the bases of each of the wanderer spindles and carry same, the guiding lugs of said wanderer spindles being free from bearing relationship over the major part of their travel; members adapted to circumferentially surround said notched discs and lie in the same plane thereof to retain said wanderer spindles thereon; and guide members mounted on said base member under the circumferential junctions of the notched discs at which point the guiding lugs of said wanderer spindles engage said guide mem-

bers to effect directional control of said wanderer spindles.

2. Improvements connected with braiding machines comprising in combination a base member; a plurality of circumferentially adjacent notched discs in driven geared relationship mounted on said base member and adapted to engage only the bases of each of the wanderer spindles and carry same, the guiding lugs of said wanderer spindles being free from bearing relationship over the major part of their travel; a suitably shaped outer member adapted to intimately surround the outer circumferential portions of said notched discs and lie in the same plane thereof to retain said wanderer spindles thereon; a star shaped inner member adapted to intimately surround the inner circumferential portions of said notched discs and lie in the same plane thereof to retain the wanderer spindles thereon; and guide members mounted on said base member under the circumferential junctions of the notched discs at which points the guiding lugs of said wanderer spindles engage said guide members to effect directional control of said wanderer spindles.

3. Improvements connected with braiding machines comprising in combination a base member having a recess therein adapted to form an oil receptacle; a plurality of circumferentially adjacent notched discs in driven geared relationship mounted on said base member above the recess thereof and adapted to engage only the bases of the wanderer spindles and carry same, the guiding lugs of said wanderer spindles being free from bearing relationship over the major part of their travel; a suitably shaped outer cover member to said base recess adapted to intimately surround the outer circumferential portions of said notched discs and lie in the same plane thereof to retain said wanderer spindles thereon; a star shaped inner cover member adapted to intimately surround the inner circumferential portions of said notched discs and lie in the same plane thereof to retain said wanderer spindles thereon; interchangeable guide members mounted in the bottom of said base recess under the circumferential junctions of said notched discs at which point the guiding lugs of said wanderer spindles engage said guide members to effect directional control of said wanderer spindles.
